UNITED STATES PATENT OFFICE.

CHARLES LAURENT GAETAN BIANCHINI, OF PARIS, FRANCE.

DESIGN FOR FABRIC USED IN UPHOLSTERING AND DECORATING.

58,870.

Specification for Design.

Patented Sept. 6, 1921.

Application filed January 29, 1921. Serial No. 441,048. Term of patent 7 years.

To all whom it may concern:

Be it known that I, CHARLES LAURENT GAETAN BIANCHINI, a citizen of the Republic of France, resident of the city of Paris, France, have invented a new, original, and ornamental Design for Fabric Used in Upholstering and Decorating, of which the following is a specification, reference being had to the accompanying drawing, forming part thereof.

The figure is a plan view of the fabric used in upholstering and decorating, showing my new design.

I claim:

The ornamental design for fabric used in upholstering and decorating, as shown.

In testimony whereof, I affix my signature this 15th day of December A. D., 1920.

CHARLES LAURENT GAETAN BIANCHINI.
